[57] CLAIM

The ornamental design for an automotive engine analyzer, as shown and described.

DESCRIPTION

FIG. 1 is a right side elevational view of an automotive engine analyzer showing our new design, the left side being a mirror image thereto;

FIG. 2 is a front elevational view thereof;

FIG. 3 is a top plan view thereof;

FIG. 4 is a bottom plan view thereof; and

FIG. 5 is a rear elevational view thereof.

FIG. 1

FIG. 2

FIG. 3

FIG. 4

FIG. 5
